(57) **CLAIM**

The ornamental design for a machine for the application of thermofusible products, as shown and described.

DESCRIPTION

The patent or application file contains at least one drawing executed in color. Copies of this patent with color drawing(s) will be provided by the Patent and Trademark Office upon request and payment of necessary fee.

FIG. 1 is a perspective view of the machine;

FIG. 2 is a left side view of the machine;

FIG. 3 is a rear view of the machine;

FIG. 4 is an upper view of the machine;

FIG. 5 is a right side view of the machine; and,

FIG. 6 is a front view of the machine.
